(57) **CLAIM**

The ornamental design for a respiratory conduit with connector, as shown and described.

DESCRIPTION

FIG. 1 is a front, top, and left-side perspective view of a respiratory conduit with connector embodying our design; FIG. 2 is a rear, top, and right-side perspective view thereof; FIG. 3 is a front view thereof;

FIG. 4 is a rear view thereof;

FIG. 5 is a left-side view thereof;

FIG. 6 is a right-side view thereof;

FIG. 7 is a top view thereof; and,

FIG. 8 is a bottom view thereof.

The break lines indicate that the appearance of any portion of the respiratory conduit with connector between the break lines forms no part of the claimed design.
